GOLF CLUB HEAD OR SIMILAR ARTICLE

Eli Romero, R.R. 1, Goddard, Kans. 67052

Filed Apr. 10, 1972, Ser. No. 242,909

Term of patent 14 years

Int. Cl. D21—02

U.S. CL. D34—5 GH

FIG. 1 is a side elevational view of a golf club head showing my new design;

FIG. 2 is a bottom plan view of the head;

FIG. 3 is a front view of the head;

FIG. 4 is a perspective view of the head; and

FIG. 5 is a perspective view of the head taken from a lower right position relative to FIG. 4.

I claim:

The ornamental design for golf club head, or similar article, as shown.
